UNITED STATES PATENT OFFICE.

MAX HENKELS, OF LANGERFELD, NEAR BARMEN, GERMANY.

DESIGN FOR LACE.

45,422.

Specification for Design.

Patented Mar. 17, 1914.

Application filed December 19, 1913. Serial No. 807,800. Term of patent 14 years.

To all whom it may concern:

Be it known that I, MAX HENKELS, a subject of the German Emperor, residing at Langerfeld, near Barmen, Westphalia, Prussia, Germany, have invented a new, original, and ornamental Design for Lace, of which the following is a specification, reference being had to the accompanying drawing, forming part thereof.

The figure is a plan view of a piece of lace showing my new design.

I claim:

The ornamental design for lace as shown. In testimony whereof, I have signed my name to this specification in the presence of two subscribing witnesses.

MAX HENKELS. [L.S.]
